UNITED STATES PATENT OFFICE

104,588

DESIGN FOR A DISPLAY RACK

Robert L. Swartwout, Albion, Mich., assignor to Union Steel Products Company, Albion, Mich.

Application March 1, 1937, Serial No. 67,933

Term of patent 7 years

To all whom it may concern:

Be it known that I, Robert L. Swartwout, a citizen of the United States, residing at Albion, in the county of Calhoun and State of Michigan, have invented a new, original, and ornamental Design for a Display Rack, of which the following is a specification, reference being had to the accompanying drawing, forming part thereof.

The figure is a perspective view of a display rack, showing my new design.

I claim:

The ornamental design for a display rack, as shown.

ROBERT L. SWARTWOUT.
